CERAMIC CORE ELECTROMAGNETIC FORMING COIL

This invention relates to forming apparatus and, more particularly, to apparatus for forming material by energy acquired from a varying magnetic field.

Apparatus has been developed for forming materials by employing varying magnetic fields of high intensity. An example of such apparatus is shown and described in the U.S. Pat. No. 2,976,907, issued Mar. 28, 1961, and assigned to the assignee of the present invention. In apparatus of this general type, an electric current pulse of high amperage is passed through a forming element comprising a conductor (e.g., in the form of a coil) to provide a desired magnetic field of high intensity. The current pulse may be applied to the conductor directly from a current pulse source or may be induced in the conductor by suitable inductive elements positioned adjacent thereto.

A conductive workpiece, positioned in the pulsed magnetic field produced by the conductor, has a current pulse induced in it. This current pulse interacts with the pulsed magnetic field to produce a force acting on the workpiece. If the force is sufficiently strong, a deformation of the workpiece results. The shape of the deformation is dependent upon the distribution in time and space of the magnetic field and the position of the workpiece relative to the field. Repeated pulses of current may be applied to or induced in the conductor, thus causing a series of deforming impulses to act upon the workpiece.

The conductors used in magnetic forming apparatus are subject to severe forces during forming of the workpiece. In order that a nonyielding reaction will be furnished to the mechanical forces associated with the high strength magnetic field, the conductor is supported against movement relative to the workpiece. In the case of a helical coil, such support may be furnished in the form of a cylindrical support member positioned within the helical conductor with its outer surface in contact therewith and coaxial therewith. In the case of a spiral conductor configuration, the support therefor may be furnished by a suitable planar support member positioned in contact with one side of the conductor perpendicularly of the axis thereof. In order to avoid current flow, and hence a reduction in the efficiency of the forming apparatus, the support member utilized should have a high dielectric strength (i.e., high electrical resistance). Typical materials heretofore utilized as support members, such as composites of fiberglass, although having high compression strength, have also exhibited a low modulus of elasticity, typically considerably lower than the material of the conductor itself. As a result, loading forces transmitted by the conductor to the support member may cause excessive compression thereof and a corresponding excessive strain on the conductor. Energy stored in the support member as a result of the compression can result in oscillation, conductor damage from rebound, and deterioration due to fatigue.

During operation of magnetic forming apparatus, repeated pulsing produces a considerable amount of heat in the conductor due to ohmic losses therein. If such heat is not adequately removed, structural damage to the conductor may result. In addition, a high operating temperature may cause a reduction in efficiency due to an increase in the resistance of the conductor to the passage of current therethrough. Accordingly, many conductors in magnetic forming apparatus have been made hollow and a cooling fluid has been circulated through the conductor itself. As a result, the number of possible coil designs has been somewhat limited due to the necessity for incorporating coolant flow passages in the conductor.

It is an object of this invention to provide improved magnetic forming apparatus.

Another object of the invention is to provide magnetic forming apparatus in which forces loading the conductor are transferred to a supporting member with a minimum strain on the conductor.

A further object of the invention is to provide magnetic forming apparatus in which cooling of the conductor is ef-

fected without utilizing coolant flow passages in the conductor.

Other objects of the invention will become apparent to those skilled in the art from the following description, taken in connection with the accompanying drawings wherein:

FIG. 1 is a full section side view of magnetic forming apparatus constructed in accordance with the invention;

FIG. 2 is an end elevational view of the apparatus of FIG. 1;

FIG. 3 is a partial side elevational view of the apparatus of FIGS. 1 and 2;

FIG. 4 is a full section side view of a portion of a further embodiment of the invention;

FIG. 5 is an end section view of still a further embodiment of the invention;

FIG. 6 is a side elevational view of the apparatus of FIG. 5, and

FIG. 7 is a full section side view of a still further embodiment of the invention.

Very generally, the apparatus of the invention, as illustrated herein, comprises a conductor responsive to pulses of electrical energy applied thereto to conduct a current for producing a magnetic field for forming a workpiece disposed in the magnetic field. A support member supports the conductor and is

comprised of ceramic material. The support member has a uniform unbroken surface. The conductor is of square or rectangular cross section and has one surface which mates with the uniform surface of the conductor to conduct a substantial amount of heat from the conductor. Means are provided for removing heat from the support member to thereby cool the conductor.

Referring now particularly to FIGS. 1 to 3, the apparatus illustrated therein is for producing an expansion type deformation in a workpiece which is positioned surrounding the conductor 11. The working part of the conductor 11 consists of a series of helical turns 12, the conductor in this region being of a relatively flat rectangular cross section. The conductor further includes a pair of hollow cylindrical sections 13 and 14, one at each end of the section of helical turns 12. A relatively wide opening or gap 16 is provided between the cylindrical section 14 and the adjacent helical winding 12 to provide a flux return path for the magnetic field established by the conductor. A similar opening or gap 17 is provided between the cylindrical section 13 and the closest of the helical loops 12.

Current is supplied to the conductor 11 through a broad flat terminal plate 18. The terminal plate is provided with a slit 19 therein and with a central opening 21 through which the cylindrical section 13 of the conductor 11 passes. The cylindrical section 13 is secured to the plate 18 by means of a bolt, not illustrated, which passes through an appropriate hole 22 in the terminal plate near the end of the slot 19 to draw the opposite faces of the slot toward each other and thus clamp the cylindrical section 13 in the opening 21. Suitable means, not illustrated, are connected to the terminal plate 18 for supplying current pulses thereto.

The current pulse, after passing through the conductor 11, is returned via a return conductor 23. The return conductor 23 consists of a tube located coaxial with the axis of the helical turns 12 of the conductor 11. The return conductor 23 is connected to the cylindrical section 14 of the conductor 11 by means of an end fitting 24 of conductive material. The fitting 24 has a projection 26 through which an opening 27 is provided, and has a circular outer periphery which mates with the inner wall of the cylindrical section 14. The return conductor 23 fits within the opening 27 in contact with the end fitting 24.

The outer surface of the conductor 11 is covered by an outer sheet 28 of a suitable insulating material, such as epoxy. An end cover 29 of a suitable insulating material closes the open end of the cylindrical sheet 28 and covers the end fitting 24 and the end of the return conductor 23. The edge of the cylindrical outer sheet seats in an annular recess 31 provided in the outer periphery of the end cover 29.

The end of the return conductor 23 opposite the end fitting 24 is surrounded by a cylindrical return conductor terminal 32, passing through a central opening 33 therein and in contact therewith. The return conductor terminal 32 is supported within a circular opening 34 in a projecting portion 36 of a return conductor terminal plate 37. The projecting portion 36 of the plate 37 defines a generally U-shaped recess 38 within which the inner end of the return conductor terminal 32 terminates. A split or slot 39 is provided in the return conductor terminal plate 37. The return conductor terminal 32 is clamped in the opening 34 by means of a bolt, not shown, extending through a hole 41 provided near the open end of the slot 39. When the bolt is tightened, the opposite faces of the slot 39 are drawn toward each other, thus clamping the return conductor terminal 32 in the opening 34. The terminal plate 37 and the terminal plate 18 are secured together against a layer 42 of insulating material by suitable insulated means, not illustrated, such as bolts.

The conductor 11 is supported internally by a support member 43. The outer surface of the support member is cylindrical and is uniform and unbroken, that is, uninterrupted by grooves or other irregularities. The rectangular cross section conductor has its inner surface in mating contact with the cylindrical surface of the support member. The support member 43 is hollow, having a generally cylindrical inner surface 44 for accommodating the return conductor 23. During operation of the apparatus, the conductor 11 is subject to high forces acting radially inward. In order to resist such forces with minimum strain of the conductor, the support member 43 is comprised of a dense ceramic material which exhibits good electrical insulating properties and a very high compression strength and high modulus of elasticity and an exceptionally high thermal conductivity. Two dense ceramic materials which are of particular advantage are aluminum oxide (Al_2O_3) and beryllium oxide (BeO). (BeO has a thermal conductivity close to that of aluminum metal). As a result, deformation of the metallic conductor 11 during operation of the apparatus is minimized, the conductor loading being transferred to the ceramic support member with minimum strain of the conductor. The large "flat" surface area of engagement between the conductor and the support member provides good thermal transfer and distributes bearing loads evenly.

During magnetic forming operations which require repeated and rapid pulsing of current through the conductor, the conductor may heat up due to ohmic losses therein. The configuration of the apparatus illustrated in FIGS. 1 to 3, and the particular material of which the support member 43 is constructed, enables efficient cooling of the conductor to be accomplished without the necessity of providing coolant passages within the conductor itself. An annular gasket or seal 46 is provided between the end of the support member 43 and the end fitting 24. This seals the region within the hollow conductor 43 from the outside at the projecting end. The return conductor 23 is made hollow, defining a passage 47. The outer wall of the return conductor 23 and the inner wall 44 of the support member 43 are spaced from each other to define a passage 48. One or more openings 49 are provided in the return conductor 23. The openings 49 communicate between the passage 47 and the passage 48. A connector tube 51 is provided communicating with the passage 47 at the end thereof opposite the openings 49. The tube 51 is adapted for connection to a source of pressurized coolant, such as a source of pressurized water, such that coolant flows axially through the passage 47 and is then forced through the openings 49 into the passage 48.

The return conductor terminal 32 is spaced axially from the closest end of the support member 43, defining an annular chamber 53. The passage 48 terminates in the annular chamber 53 and coolant accumulating in the annular chamber 53 is passed through a passage 54 provided in the return conductor terminal 32 into a connector tube 56 attached thereto. Suitable means, not illustrated, are connected to the tube 56 for collecting the outflowing coolant from the tube. Because

of the ceramic material's strength, its impervious character, and its exceptionally high thermal conductivity for an electrical insulator, the support member 43 readily transfers heat from the conductor 11 to the coolant flowing through the passage 48. Because of this, the conductor 11 may be made solid, rather than having coolant passages therein, allowing for greater flexibility in design.

In order to seal the annular chamber 53 against leakage of coolant into the recess 38, a seal sleeve 57 is provided. The sleeve 57 extends over the outer periphery of the chamber 53 and beyond the edges thereof a sufficient distance as to allow the use of a pair of annular seals 58 and 59 near the opposite ends of the sleeve 57. This seals the chamber 53 against leakage. The resultant construction makes possible the positioning of the two tubes 51 and 56 adjacent each other, affording some convenience in design. Moreover, the compliant nature of the arrangement of the sleeve 57 and the seals 58 and 59 avoids the accidental application of undesirable forces to the ceramic support member 43 during assembly or operation. Under some circumstances, a rigid seat termination of the support member 43 within the return conductor terminal plate 37 may cause excessive loading and damage to the support member through minor misalignment of its parts during assembly or through vibration of the parts during operation.

In the event that extraneous loads on the supported end of the support member can be tolerated, and that nonadjacent positioning of the inlet and outlet coolant connections can also be tolerated, the apparatus of the invention may be constructed as illustrated in FIG. 4. In the embodiment of FIG. 4, parts therein having functions identical with parts in the embodiment of FIGS. 1 to 3 have been given identical reference numbers preceded by a one. Thus, the conductor 111, having a plurality of helical turns 112, is supported on a dense ceramic hollow support member 143. A support cylinder 161 of a suitable rigid insulating material is disposed coaxially around the cylindrical section 113 of the conductor 111. The outer sheet 128 of insulation extends with the cylindrical section 113 through an opening in the cylinder 161, the entire assembly thereby being supported or cantilevered out by the cylinder. The cylinder 161 is provided with an annular flange 162 and extends through an opening 163 in a plate 164 of insulating material, the flange 162 seating in an annular recess about the periphery of the opening 163.

The cylindrical section 113 of the conductor 111 projects beyond the flanged end of the supporting cylinder 161 and is clamped within the terminal plate 118. The terminal plate 118 is split or slotted at 119 and is provided with a bolt hole 122 for clamping the opposite faces of the slot 119 toward each other and thereby clamping the cylindrical section 113 within the opening 121 provided in the terminal plate 118. An input conductor plate 166 is bolted to the terminal plate 118 for conducting current pulses thereto.

The return conductor 123 consists of two layers—copper sheath over stainless steel. The return conductor which, as in the previously described embodiment, extends through the hollow interior of the support member 143, is clamped in an opening 167 in the return conductor terminal plate 137. The return conductor terminal plate 137 is brazed to the return conductor 123 in electrical contact with the terminal plate 137. The opening 167 is provided with a series of sections or steps of different diameters and thereby also accommodates the end of the support member 143. An annular seal 168 is provided surrounding the end of the support member 143 between the support member and the return conductor terminal plate 137. The next adjacent step in the opening 167 is sufficiently large to provide a space 170 between the return conductor 123 and the return conductor terminal plate 137. The seal 168 seals this space. Current is conducted from the return conductor terminal plate 137 by a conductive plate 169 bolted thereto.

A fitting 171 is bolted to the return conductor terminal plate 137 over the end of the return conductor 123. The fitting 171 includes a recess 172 and a passage 173 for inlet coolant

which forms a fluid path to the interior of the return conductor 123. The recess 172 is sealed by an annular seal 175 which surrounds the recess at the interface between the return conductor terminal plate 137 and the fitting 171. Coolant flowing through the return conductor is returned through the passage 148 outside the return conductor to the space 170 between the opening 167 and the outer surface of the return conductor 123. This space is drained by a passage 174 in the return conductor terminal plate 137. The passage 174 is shown in dotted lines since it is out of its normal position in the drawing by 90°.

Under some circumstances, the high heat transfer capacity of the dense ceramic material of the support member for the conductor may allow an arrangement such as is illustrated in FIGS. 5 and 6. In the embodiment of FIGS. 5 and 6, parts therein having functions similar to parts in the embodiment of FIGS. 1 to 3 have been given identical reference numbers preceded by the number 2. Thus, the embodiment of FIG. 5 and 6 includes a conductor 211 having a plurality of helical turns 212 and a pair of cylindrical sections 213 and 214 at opposite ends. The conductor 211 is disposed upon a hollow cylindrical support member 243 of a dense ceramic material and is covered by an outer sheet 228 of insulating material. The outer sheet 228 is closed at one end by an end cover 229, also of insulating material.

In the embodiment of FIGS. 5 and 6, the return conductor 223 is solid, no coolant being passed therethrough. Electrical connection between the solid conductor 223 and the cylindrical section 214 of the conductor 211 is made by means of a conductive end fitting 224. The fitting 224 is generally circular in shape and has a central opening therein for accommodating the solid return conductor 223. A terminal plate 218 conducts current pulses to the cylindrical section 213 of the conductor 211. The terminal plate 218 is provided with a thick section 276 and has a split or slot 219 therein and a central opening 221 in which the cylindrical section 213 is accommodated. A bolt hole 222 allows the facing surfaces in the slot 219 to be drawn toward each other and thus clamp the cylindrical section 213 in the terminal plate 218. Since the support member 243 has an outer surface in mating engagement with the inner surface of the cylindrical section 213, the support member is also clamped within the terminal plate opening 221. As may be seen in FIG. 5, the thickened section 276 of the terminal plate 218 is provided with fluid conducting passages 277 and 278 therein. The passage 277 includes an inlet orifice 279 and an outlet orifice 281. Similarly, the passage 278 includes an inlet orifice 282 and an outlet orifice 283. The passages 277 and 278 are bored through the thickened section 276 and are, therefore, sealed with plugs 284 and 286, respectively.

The return conductor 223 passes beyond the end of the support member 243 and fits within an opening 267 in a return conductor terminal plate 237. The terminal plate 237 includes a thickened portion 287 and is shown as a solid member in which the opening 267 is provided and in which the solid conductor 223 may be force fit or welded for proper connection. Alternatively, a split plate connection in the terminal plate 218 may also be utilized, as shown in the previous embodiments. The terminal plate 218 and 237 are separated by a layer of insulation 242, being bolted against opposite sides thereof by suitable means, not illustrated.

The high thermal conductivity of the ceramic material of the supporting member 243 enables the supporting member to conduct heat from the conductor 211 to the heat sink in the terminal plate 218. Accordingly, no fluid circulation need be provided within the support member 243, making the construction somewhat simpler than in the previous described embodiments.

In the previously described embodiments, the nature of the conductor was such as to provide expansion deformation forces on a workpiece positioned around the conductor. If unidirectional forces rather than radial forces are desired, a construction such as is shown in FIG. 7 may be utilized. The conductor 301 therein is of generally square cross section and

includes a plurality of turns 302 in the form of a flat spiral. When current pulses are passed through the windings 302, forces are produced which are exerted generally parallel with the axis of the spiral (vertical in the drawing). In order to support the conductor 301 against such forces, a support member 303 is provided. The support member 303 has a generally circular outer periphery and is of a thickness about 1/7th to 1/6th the diameter. A central opening 304, elongated in the direction perpendicular to the paper in the drawing, is provided in the support member 303. A high voltage conductor plate 306 is passed through the opening 304 and is secured in electrical contact to the innermost end of the spiral conductor 301.

The support member 303 rests in an annular recess 307 formed in a return conductor ring 308. The upper surface of the support member 303 is flush with the upper edge of the ring 308, and the outermost turn of the conductor 301 is bolted to the return conductor ring 308 by a plurality of bolts 309. The bolts 309 also secure a flat sheet 311 of insulating material over the top surface of the conductor 301 for protecting same.

A fluid manifold 312 is provided just beneath the support member 303. The fluid manifold 312 is of an electrically conductive material and is provided with a central opening 313 therein for accommodating the plate 306 in a spaced relation to prevent shorting. The upper surface of the fluid manifold 312 is provided with an annular recess 314 therein, and is also provided with a pair of concentrically disposed ring seals 316 and 317 for sealing the recess 314 against the underside of the support member 303. A fluid conducting inlet tube 318 passes through the fluid manifold 312 and communicates with the recess 314 at one side thereof. At the opposite side, a fluid drain tube 319 communicates with the recess 314, passing through the fluid manifold 312. The fluid manifold is secured and clamped to the underside of the support member 303 by a clamping ring 321 which extends around the lower edge of the terminal ring 308 and extends inwardly of the inner surface thereof to overlap the fluid manifold 312 on its lower surface. A plurality of bolts 322 are provided to secure the clamping ring 321 against the terminal ring 308.

The electrical return for the conductor 302 is provided by a return conductor plate 323. The plate 323 is provided with a flange 324 extending outwardly near its upper edge. The flange 324 is captured between the lower surface of the fluid manifold 312 and a lower cover plate 326. The lower cover plate 326 is secured to the clamping ring 321 by a plurality of bolts 327, and is provided with openings 328 and 329 therein for accommodating the tubes 318 and 319, respectively. A sheet 331 of insulation material is disposed between the conductive plates 306 and 323. Accordingly, flow of current pulses to the conductor 302 is through the plate 306 to the centermost termination of the conductor. Return flow is from the outer periphery of the conductor through the terminal ring 308, the fluid manifold 312, the flange 324 and the conductor 323.

The material of which the support member 303 is comprised is the same as that described in connection with the support members of the previous embodiments. Accordingly, the thermal conductivity thereof is relatively high and heat is adequately removed from the conductor 301 through the support member 303 to the coolant circulated in the recess 314. Moreover, because of the high compression strength and high modulus of elasticity of the material, good support is given to the conductor against deforming forces such that strain on the conductor is minimized. Good thermal transfer and load distribution is attained due to the effect of one surface of the rectangular or square cross section conductor being flush or in mating engagement with the uniform unbroken surface of the support member.

It may therefore be seen that the invention provides improved magnetic forming apparatus in which satisfactory support for the conductor of the apparatus is provided with minimum strain exerted on the conductor during high current

periods. Moreover, satisfactory heat removal from the conductor is possible without the necessity of providing for coolant passages within the conductor itself.

Various modifications of the invention in addition to those shown and described herein will become apparent to those skilled in the art from the foregoing description and accompanying drawings. Such modifications are intended to fall within the scope of the appended claims.

We claim:

1. A forming element for use in magnetic forming apparatus, comprising, a conductor having a plurality of turns and being responsive to pulses of electrical energy applied thereto to conduct a current for producing a magnetic field for forming a workpiece in the magnetic field, a support member comprised of ceramic material positioned in direct contact with said conductor on the side thereof opposite to the workpiece for supporting said conductor against forces exerted on said conductor during forming of a workpiece, and means for removing sufficient heat from a surface of said support member opposite the conductor to cool said conductor, said support member being a solid continuous mass with a uniform unbroken supporting surface extending across the gaps between the turns of said conductor, and said conductor being of rectangular cross section and having one surface flush against said supporting surface of said support member along the length of said conductor providing a substantial area of direct contact therebetween.

2. A forming element according to claim 1 wherein said conductor is of helical configuration and wherein the supporting surface of said support member is cylindrical and is coaxial with said helical conductor.

3. A forming element according to claim 1 wherein said

conductor is of spiral configuration and wherein said supporting surface of said support member is planar and is perpendicular to the axis of said spiral conductor.

4. A forming element according to claim 1 wherein said heat removing means include a heat sink in contact with a further surface of said support member, and further include means for passing a circulating fluid coolant in contact with a surface of said heat sink.

5. A forming element according to claim 1 wherein the ceramic material of which said support member is comprised consists of beryllium oxide.

6. A forming element according to claim 2 wherein said support member is hollow, said forming element further including a return conductor comprising a hollow tube disposed centrally of said support member for providing a return current path from said conductor, said return conductor being spaced radially from the inner wall of said support member to form a pair of concentric coolant flow passages.

7. A forming element according to claim 6 including coolant conducting means spaced axially from one end of said support member, and including a seal sleeve disposed about the space between said coolant conducting means and said support member to define a chamber for coolant flow between said coolant conducting means and said support member without direct contact therebetween.

8. A forming element according to claim 2 wherein said support member is hollow, said forming element including a return conductor extending through the hollow interior of said support member for conducting current from said conductor, and a fluid cooled heat sink disposed in contact with one end of said support member for removing heat therefrom.
